(57) **CLAIM**

The ornamental design for a lounge chair beach towel, as shown and described.

DESCRIPTION

FIG. 1 is a top plan view of a lounge chair beach towel showing my new design;

FIG. 2 is a bottom plan view thereof;

FIG. 3 is a right elevation view thereof, the opposite side being a mirror image of that shown;

FIG. 4 is a front elevation view thereof;

FIG. 5 is a rear elevation view thereof; and,

FIG. 6 is an isometric view thereof, shown in use.

The broken lines in the drawings depict environmental subject matter only and form no part of the claimed design.
